UNITED STATES PATENT OFFICE.

GEOEGE E. HADLEY AND WILLIAM E. RILEY, OF LOUISVILLE, KENTUCKY.

TOWEL-DISPENSING CABINET.

1,380,648.

Specification of Letters Patent. Patented June 7, 1921.

Application filed September 23, 1920. Serial No. 412,185.

To all whom it may concern:

Be it known that we, GEORGE E. HADLEY and WILLIAM E. RILEY, citizens of the United States, and residents of Louisville, in the county of Jefferson and State of Kentucky, have invented an Improvement in Towel-Dispensing Cabinets, of which the following is a specification.

Our invention relates to a new and useful improvement in dispensing cabinets for towels, and consists of certain improvements, and of a certain new and novel construction, fully set forth in the following specification, and shown in the accompanying drawings forming a part hereof.

Our invention has for one object the provision of a method and means of uniformly folding, stacking and securing, under lock and key, the number of towels allocated to a customer before the allotment leaves the laundry office, thus insuring the return of the same number of towels after they have been used, and keeping them under lock and key while they are in use and while in transit to and from the laundry, at the same time preventing the improper use of towels for purposes other than personal toilet, thus avoiding the great loss of towels, now so common in the industry, and insuring the delivery of the number of towels allocated to a customer.

Another object is to provide a closed and locked cabinet, in which the towels are placed pending use, from which they may be withdrawn, one after the other, thus avoiding the contamination of the towels, prior to their use, by dust, dirt, soot and other atmospheric influences.

Another object is to provide a means by which a user will secure an individual towel without contaminating any of the other towels by drippings from his or her hands or by touching any other towel in the cabinet.

And a further object is to provide a dispensing cabinet from which the towels stacked therein may be successively withdrawn by taking hold of the corner of the lowest towel and pulling the same through a slotted-triangular opening in the bottom of

the cabinet, the towel, when removed, following a flexible retainer, thus disposing of the soiled towel, and at the same time permitting the convenient and comfortable use of the towel, as far as the hands and face

are concerned, quite a distance from the cabinet.

The purpose of the slotted-triangular opening, through which the towels are drawn, is to provide just the character, shape and size of opening found by practice to be necessary to permit the ready release of the under towel of a stack of towels and at the same time to leave so much of the bottom as has been found necessary to support what remains in the stack of towels and avoid the bulging of the mass of towels through the opening.

These specifications set forth the embodiment of our invention as it is preferred, but it is to be understood that such changes and modifications may be resorted to as come within the scope of the claims appended hereunto.

With the above and other objects in view our invention has particular relation to certain novel features of construction, more fully set forth in the accompanying drawings wherein:

Figure 1 is a perspective view of the device in its normal condition.

Fig. 2 is a similar view showing the cabinet open, wherein the towels are to be stacked ready for use, with the front of the receptacle for soiled towels partly broken away to show the position the towels take after use.

Fig. 3 is a vertical sectional view showing the holding element attached to the inside of the top of the cabinet, with the guide member and the lock, also the flexible part of said member, including the cotter-pin at the end of the flexible part of the guide member.

Fig. 4 a plan view of the bottom of the cabinet, on line 4—4 of Fig. 3, showing the slotted-triangular opening.

Fig. 5 a sectional view of the holder, with the guide member in place.

Fig. 6 a perspective view of the stacking plate, showing the rod on which the desired number of towels are stacked, also showing the guide post and a towel folded.

Fig. 7 a sectional view of the stacking rod, seated in the metal thimble.

Fig. 8 a detailed view of the guide member.

Fig. 9 a perspective view of a stack of towels, with securing band, guide member positioned within the gromets and with lock and cotter-pin attached.

110

Similar numbers refer to similar parts throughout the several views.

The apparatus comprises a cabinet, 20, in which towels are stacked, 21, standards, 22, supporting the cabinet, an open receptacle, 23, to receive soiled towels, a guide member, 24, with flexible part, 25. The guide member, 24, is provided with apertures, 26, in which a lock, 27, is secured, and a depression, 28, 10 in which the spring clasp, 29, engages, another aperture, 30, near the delivery end of the rigid part of the guide member, in which the cotter-pin is positioned when towels are stacked, a holder, 32, rigidly attached to the 15 inside of the top of the cabinet, 33, designed to hold the guide member when in normal position in the cabinet, said holder having a vertical aperture into which the guide member is slipped, a spring clasp, 29, operative within the holder and designed to seat in the slot, 28, thus securing the guide member until the clasp, 29, is pulled out by the knob. A slot, 34, is cut in the upper end of the guide member which engages 25 the set screw, 35, thus retaining the guide member in proper position. Rigidly attached to the guide member, 24, is a flexible chain, wire or cord, 25, which serves to carry the soiled towels to the receptacle, 23. 30 At the end of the flexible part of the guide member is securely attached a cotter-pin, 31, the head of which is too large to permit the passage of the gromet, 36, of the towel. Each towel is provided with a gromet, 36, 35 or has a hole punched to fit over the guide member, 24. The cabinet is provided with a swinging door, 38, with a looking glass front, if desired. In the upper front part of the receptacle for soiled towels is a box, 40, for the storage of soap, combs and brushes. As a part of the device a stacking plate, 41, is provided, in which a thimble, 42, is embedded and in which a stacking rod, 43, is positioned. The towels are stacked, 45, as shown in Fig. 9, after being folded as shown in Fig. 6.

The parts will be assembled normally as shown in Figs. 1 and 2, with the desired allotment of towels, say number up to a hundred or so, stacked, 21, within the cabinet and held in position by the guide member, 24, with the cotter-pin, 31, properly positioned and resting within the receptacle, 23. The guide member is held rigidly in position by the holder, 32. The bottom of the rigid part of the guide member is slightly bent and is held a short distance above the bottom of the cabinet and positioned in proper relation to the slot, 43, of the triangular opening, 44.

It will be noticed that a corner of the bottom towel $21\frac{1}{2}$, projects below the bottom of the cabinet, and all one needs to do is to pull on that corner, when the towel will 65 come through and the corner of the towel

next above will fall through the opening and be ready for removal, and so the process may be repeated until all towels in the cabinet have been removed.

In preparing the towels at the laundry or 70 at headquarters for distribution the stacking plate, 41, is used, with the rod, 43, positioned in the thimble, 42, the gromet of a towel slipped over the rod, then the loose end of the towel is brought forward to within a 75 short distance of the rod and opposite the guide post, 47, and the towel creased at the fold. This operation is repeated until the desired number of towels has been stacked on the rod; a paper band is then folded 80 around the stack and securely fastened. The rod is then lifted out, and the guide member with the cotter pin adjusted, is then slipped, upper end foremost, down through the gromets, the stack of towels turned over 85 and the lock, 27, inserted and locked in one of the apertures, 26, nearest to the towels.

A supply of stacks of towels may be kept on hand at headquarters, always in readiness to replenish the cabinets. An extra supply may be kept on the customer's premises and he, being furnished with a key to the cabinet door, may replenish the cabinet from time to time. However, it will require very little of the time of the agent to 95 remove the soiled towels and replenish the cabinet with clean towels.

After the stack of clean towels has been placed in the cabinet, the guide member adjusted in the holder, the cotter-pin released 100 and dropped into the receptacle for soiled towels, the paper band is torn off and the towels are ready for service.

This device may be supplemented by a coined controlled mechanism.

Having thus described our invention, we claim—

1. A towel dispensing cabinet including an upper compartment with means for opening, closing and locking the same, proper supports to retain said compartment at the desired elevation, a slotted opening in the bottom of said compartment, means for supporting a stack of towels, a receptacle for soiled towels, a guide member, part rigid and part flexible, the rigid part provided with perforations, the flexible part rigidly attached to the rigid part, and long enough to reach into the soiled towel compartment, said guide member having at the lower end 110 a cotter-pin large enough to prevent the passage of the gromets in the towels, the upper compartment also having a spring latch holder for holding the guide member in proper position above said slotted opening, said opening being so formed that the bottom will support a stack of towels resting on the same but permitting a corner or a portion of each succeeding towel, from the bottom of the stack up, to fall in view and 120 125 130

in such position so that said part may be readily grasped for the purpose of pulling said towel through said opening, all substantially as set forth.

- 5 2. In a device of the character described, for dispensing towels or like articles, a cabinet or box, with door and lock, and with a slotted-triangular opening in the bottom, said bottom and opening designed so as to
10 permit the descent, suspension and withdrawal, through said opening, of a corner or a part of a towel, or other like article, the remainder of the stack supported above by the part of the bottom not cut away, said
15 cabinet having the necessary supports to hold said cabinet at the desired elevation, and a compartment forming a receptacle for soiled towels positioned below said cabinet, in combination with a holder, rigidly attached to the ceiling of the cabinet or box, a
20

guide member, comprising a rigid and a flexible part, designed to be positioned in and to be held by said holder, said guide member to extend through the gromets or holes in a stack of towels, or like articles, 25 piled within the cabinet, and to extend through the opening in the bottom of the cabinet down into the receptacle for soiled towels, said rigid part having means of attachment to the holder, further means for 30 receiving a padlock and a cotter pin, to aid in holding the towels in place on, and to prevent removal of the towels from the guide member, all substantially as set forth and described herein. 35

In testimony whereof we have affixed our signatures this the 22d day of September, 1920.

GEORGE E. HADLEY.
WM. E. RILEY.
